SEESAW CONVERTIBLE TO A SLIDE

Isadore J. Rocklin, Sioux City, Iowa.

Application August 23, 1946, Serial No. 692,478

2 Claims. (Cl. 272—55)

1

My invention pertains to a child's gymnasium apparatus.

An object of my invention is to provide such an apparatus which can be used as a bouncing spring board, and which spring board can be changed as desired to a slide, or a ring apparatus.

A further object of my invention is to provide means for changing to the alternate forms in a unit construction without requiring any extra parts, or the like.

A further object of my invention is to provide such a spring board simulating riding action on a horse, with certain arrangements for providing a spring urged bouncing action.

A further object of my invention is to provide means cooperator with the spring board arrangement so that it will readily provide the slide features when changed to the slide form.

A further object of my invention is to provide the above mentioned objects in a simple construction.

With these and other objects in view, my invention consists in the construction, arrangement, and combination of the various parts of my device, whereby the objects contemplated are attained, as hereinafter more fully set forth, pointed out in my claims, and illustrated in the accompanying drawings, in which:

Figure 1 is a side elevation of the arrangement when used as a bouncing board.

Figure 2 is a plan view of Figure 1.

Figure 3 is a rear end view of Figure 1.

Figure 4 is a sectional detail taken along the lines 4—4 of Figure 3.

Figure 5 is a view of the arrangement when used as a slide.

Figure 6 is a view of the arrangement when used as a ring apparatus.

Figure 7 is a slightly modified form of the arrangement.

Figure 8 is a rear view of Figure 7, and

Figure 9 is a view of the arrangement shown in Figure 7 when used as a slide.

I have used the character 10 to designate a pair of vertical posts having the transverse base 11 attached thereto. A pair of spacers 12 are positioned adjacent to the upper ends of the posts 10 and attached at 13 to the spacers are a pair of side stair members 14 between which are attached the flat steps 15 and attached across the bottom of the members 14 is a further member 16. Received through the members 12 and the posts 10 and the members 12 and 14, and which is securely held in place by means of the arcuate bands 19 which are retained by means of the

2

bolts 20 which pass through the members 10. Received between the members 14 is an extending portion 21 of the substantially lengthened flat board 22, the shaft 17 being attached thereto by means of the clamps 23. The board 22 includes a pair of side members 24, and continues into a seat portion 25 to which is attached at 26 the upwardly extending bar 27 which terminates in the transverse handle 28. Attached at 29 is a rope or other loop 30 and also attached substantially at the point 29 are a pair of ropes 31 which are attached at 32 to the rings 33. A pair of openings 34 are provided at the rear end of the board 22, and received within suitable openings 35 in the posts and spacers are a pair of lengthened pegs 36 which are attached to the chains 37 which chains in turn are attached to the posts.

Attached inwardly to either post 10 by means 20 of the brackets 38 are a pair of cylinders 39. The brackets 38 are rigidly attached to the posts 10 by means of a pair of bolts 40. A pair of further equally spaced openings 41 are also provided in the posts 10. Received within the cylinders 39 are 25 strong helical compression springs 42 which receive the extending portion 43 of the members 44 which are threadably engaged at 45 with the rear end of the cylinder 39. The members 44 include slots 46. The forward ends of the cylinders 39 are open, and received within this opening 47 when the arrangement is used in the spring board position are the substantially arcuate bars 48 which terminate in the ball portions 49, such ball portions being adapted to bear against the ends of the springs 42. The other ends of the bars 48 are rigidly bolted or otherwise attached at 50 to the vertical ends of the members 24.

It will be noted that the bar 48 straddles the members 14 so that the ball portion 49 will enter the cylinder and will be completely unrestricted during any movement of the board.

Figure 1 illustrates the use of the arrangement as a bounce board, or where a child simulates the action of horse riding. The child is seated on the seat 25 with his feet in the rings 33, and grasping either the handle 28 or the loop 30 as desired. As the child bounces up and down on the seat, the arms 48 will alternately compress against the spring 42 and release, thereby providing a pronounced spring action which carries the child upwardly and downwardly in a realistic manner. The spring is normally securely held on the portion 43 and the tension of the spring can be adjusted by turning the member 44 through the agency of the slot 46. In some cases it may be

desired to tilt the board 22 or elevate the seat 25, which is accomplished by moving the cylinders 39 to the right as viewed in Figure 4, until the bolts 40 can be registered with the further openings 41, the equal spacing of the openings providing as many as three adjustments. In this manner the board can accommodate larger children, or can be varied in its position to suit any desired conditions.

When used as a slide, the entire board is swung over in the direction of the arrow 51 to the position as shown in Figure 5, with the seat portion then resting on the floor surface. The child can then climb the steps 15, and thence grasping the bars 48, place himself between the side members 24 and slide down the slide thus formed, this side of the slide being suitably smooth for this purpose.

Figure 6 shows the arrangement as used as an exercising device, wherein the board 22 is elevated to a substantial angle until the openings 34 register with the openings 35, and the pegs 36 are then pushed inwardly until they pass into the openings 34. The arrangement is then in rigid position as shown, and the child will then grasp the rings 33, and swing, etc., from the same.

The straps 19 provide means for convenient assembling after packaging of the device, although it will be understood that the members can be attached in any suitable manner.

Figures 7 to 9 inclusive show the same arrangement as above described, with the exception that the spring members are altered as will now be described. The balance of the structure however, is identical to that mentioned above. In this latter modification the cylindrical members 39, springs 42, and arms 48 are not used, and instead a pair of springs 52 are attached at their upper ends to the portions 21 of the board, being solidly bolted or otherwise attached at 53 thereto. The springs 52 pass over the end of the board and are retained by means of the substantially U-shaped keeper 54, and are solidly attached at 55 to suitable bolts or the like to the inside of the vertical posts 10.

It should be noted also that in this modification, the shaft 17 is mounted at a slightly higher elevation in order to secure sufficient leverage action of the spring with respect to the end of the board, and it will also be noted that the openings 34 are located at the end of the board to accommodate the position shown in the dotted structure Figure 7 wherein the arrangement is used as more completely shown in Figure 6.

In this latter arrangement also, the springs 52 will be under tension when the child is bouncing on the board, or when the arrangement is as shown in Figure 7. When the arrangement is swung over to the slide position shown in Figure 9, the springs 52 will then be completely beneath the board and providing an unrestricted portion.

without any projections so that the child can be seated at the upper end for sliding. In this type of structure the spacer members 12 will not be required.

It will now be seen that I have provided all of the various advantages mentioned in the objects of my invention, with further advantages being readily apparent.

Some changes may be made in the construction and arrangement of the parts of my invention without departing from the real spirit and purpose of my invention, and it is my intention to cover by my claims any modified forms of structure or use of mechanical equivalents which may be reasonably included within their scope.

I claim as my invention:

1. A child's gymnasium apparatus comprising a base member, a substantially horizontal spring board member pivoted to the base, means attached between said spring board member and said base to provide a resilient spring urged action between the board and the base, means for pivoting said board on said base to an opposite position to that of the spring board position whereby said spring board will provide a slide, means for providing said spring urged action including compression springs attached to the base, bars attached to the spring board adapted to engage said springs, cylinders receiving said springs, means for adjustably tensioning said springs in said cylinders.

2. A child's gymnasium apparatus comprising a base member, a substantially horizontal spring board member pivoted to the base, means attached between said spring board member and said base to provide a resilient spring urged action between the board and the base, including compression springs attached to the base, bars attached to the spring board adapted to engage said springs, cylinders receiving said springs, means for adjustably tensioning springs in said cylinders, adjustable means for moving said cylinders to varied positions to provide desired positioning of the spring board.

ISADORE J. ROCKLIN.
